UNITED STATES PATENT OFFICE

100,521

DESIGN FOR COMBINATION BOTTLE AND HOLDER THEREFOR

Helena J. Titus, New York, N. Y.

Application May 20, 1936, Serial No. 62,737

Term of patent 7 years

To all whom it may concern:

Be it known that I, Helena J. Titus, a citizen of the United States of America and residing in the State, county, and city of New York, have invented a new, original, and ornamental Design for Combination Bottle and Holder Therefor, of which the following is a specification, reference being had to the accompanying drawing, forming part thereof.

tion bottle and holder therefor showing my new design;

I claim:

The ornamental design for combination bottle and holder therefor, as shown.

In testimony whereof, I affix my signature.

HELENA J. TITUS.
